UNITED STATES PATENT OFFICE.

RICHARD MONTGOMERY, OF NEW YORK, N. Y., ASSIGNOR TO ELIZABETH MONTGOMERY.

CORRUGATED PLATE FOR STEAM-BOILERS, &c.

Specification of Letters Patent No. 9,738, dated May 17, 1853.

To all whom it may concern:

Be it known that I, RICHARD MONTGOMERY, of the city, county, and State of New York, have invented a new and useful metal plate, in part plane and in part corrugated and of variable thickness, applicable to the construction of safes, steam-boilers, and to other purposes, of which the following is a full and exact description, reference being 10 had to the accompanying drawings, which form part of the specification, and in which—

Figure 1 represents a plan, and Fig. 2 a transverse section, of one of my new boiler plates with a series of rivet holes punched in its margin; Fig. 3 a plan of a plate with its edges upset preparatory to corrugating its middle; and Fig. 4 a transverse section of the same.

20 My invention and improvement consists in making a plate of metal, with a margin on its edges, wide enough for the rivet holes, thick, and flat, and its middle or that portion included within the margin thinner, 25 but corrugated to render it stiff, the depth of the folds of the corrugation being inversely proportioned to the thickness of the middle, so that to whatever degree it may be reduced it will still have the requisite 30 degree of lateral strength imparted to it by the corrugation.

The accompanying drawing in Figs. 1 and 2 represents the margin (A) of the plate in this instance of about double the thickness 35 of the middle (B) which is extended to double its original linear dimensions in the direction of the arrow (c), while the depth of the folds of the corrugations is such, that the plate notwithstanding its attenuation 40 will possess much greater lateral stiffness, than it would have done if left flat and of the thickness of the margin. The plate is extended but little in the direction of the length of the folds of the corrugations, and 45 this is compensated, by the protrusion of the ends (e) of the folds. The folds are thus made, and the margin left flat by a pair of fluted rolls, those parts of whose peripheries which perform the operation of 50 shaping the plate, if developed on a flat surface would respectively be the counterparts in position and shape of the two sides of the finished plate. For convenience, the rolls should be made of such diameter, that 55 from one half to three fourths only of their peripheries would be equal to the length of

the plate to be shaped, so that the time occupied in turning over the rolls the remainder of their peripheries will give an opportunity to insert the plates to be shaped between them. Those portions of the peripheries of the rolls, which correspond to the corrugations are fluted, the flutes of one roller being the counterpart of those of the other, the part corresponding to the side margins (1, 1,) of the plate, are narrow strips, concentric with the axis of the rolls, and of a width corresponding to that of the margins, while the parts which correspond to the end margins (2, 2,) are also concentric to the axis, and equidistant therefrom with the strips, which shape the side margins (1, 1,) but at right angles with the latter on the face of the rolls. The two surfaces of the rolls thus formed are each 75 the counterpart of the other, and their point of nearest approximation which is in the plane which passes through their axis, leaves a space of the proper thickness, and shape 80 for the plate.

The plate should be made white or welding hot preparatory to introducing it between the rolls and then in case no flaws exist in the original plate, the finished plate will be perfectly sound, but if it has any 85 hidden defect, the corrugating it will be certain to develop it, so that by this process of manufacture, not only does the plate receive the proper shape but its soundness is also effectually tested. A pair of rolls that 90 could with advantage be employed for the manufacture of these plates, is described in the patent granted to me on the fifth day of February 1850.

The margins of each plate can be upset to 95 any required thickness by first heating and then passing them in succession between three rolls two of which to feed and clamp the plate, and the third to upset the edge. Or a plate may be heated to a suitable heat 100 and then clamped in a vise with one edge protruding as far as it is desired to upset it, and then it may be upset by compression, or by a drop punch or swage, or a clamp may be made in two parts which will clamp 105 between them so much of the middle of the plate as is not required to be upset, and allowing the parts which are to be upset to project into a groove of a width equal to the thickness to which it is required to upset 110 the margin of the plate, and then forcing either by pressure or percussion a swage or

follower that fits the groove down upon the edge to compress it down until it fills the groove, each edge is in like manner compressed into the groove to increase its thickness and at the same time give it a symmetrical shape. In this way the margins may be made if required four, five, or more times the thickness of the middle of the plate.

- 10 I do not confine myself to the shaping of this plate in the precise manner I have specified, but leave it to the constructor to make such changes in this part of the process, as his judgment and experience may suggest.
- 15 The thick flat margins of plates, when riveted together give great stiffness to the joint and furnish a firm basis on which to head down the rivets. The reduction in thickness of the middle of the plate, and a corresponding increase of its surface, add greatly to its capacity to transmit the heat from fire or flame on one side of it, to a

liquid on its opposite side. Moreover the great comparative thickness of the plates at the base of the rivets, operates as a frame to stiffen, strengthen, and keep in place, a series of the plates riveted together, in this way, dispensing in many cases with the use of angle iron for stiffening.

The plates may be bent into any required shape either in the process of corrugating, or subsequently, to adapt them to rectangular, circular, or other structures.

What I claim as my invention and desire to secure by Letters Patent is—

35

The corrugated metal plate as herein described with flat margins of greater thickness than its middle.

In testimony whereof, I have hereunto subscribed my name.

R. MONTGOMERY.
